UNITED STATES PATENT OFFICE.

FRED F. BURDICK, OF CHICAGO, ILLINOIS.

COLLAPSIBLE CABINET.

1,066,884.

Specification of Letters Patent.

Patented July 8, 1913.

Application filed February 1, 1913. Serial No. 745,625.

To all whom it may concern:

Be it known that I, FRED F. BURDICK, a citizen of the United States, and a resident of Chicago, in the county of Cook and State 5 of Illinois, have invented certain new and useful Improvements in Collapsible Cabinets, of which the following is a specification.

This invention relates to cabinets which 10 are designed to be used for the giving of heat baths, electric light baths, Turkish, Russian, and other like baths, and which are also designed to be collapsed when not in use, and thereby be made to occupy less 15 space than when in position for use.

The object of this invention is to obtain a cabinet of the kind named which is light in weight, easily set up and collapsed; which makes a rigid and unyielding package when 20 collapsed; and a package in which the several fragile devices and parts will be well-protected from injury.

In the drawings accompanying and forming a part of this specification Figure 1 is 25 a side elevation of a collapsible cabinet embodying this invention, the several parts which are illustrated being in position for use. Fig. 2 is a top plan view, with the several parts in the same position as in Fig. 1. Fig. 3 is a side elevation of the cabinet, in a collapsed condition, with a portion of one corner broken away. Fig. 4, (Sheet 2) is a 30 side elevation of a modification of the cabinet, the several parts being in the same position as in Figs. 1 and 2. Fig. 5 is a vertical section of one corner of the cabinet, on line 35 5-5 of Fig. 2, viewed in the direction indicated by the arrows. Fig. 6 is a top plan view of the cabinet with the several parts in 40 a collapsed condition. Fig. 7 is a perspective, on an enlarged scale, of a block which forms one end of a corner of the device. Duplicate blocks are used for the several 45 corners. Fig. 8 is a horizontal section of one corner of the cabinet, on an enlarged scale, on line 8-8 of Fig. 1, viewed in the direction indicated by the arrows. Fig. 9 is a 50 vertical section of a portion of a block forming an end to one of the corners of the cabinet, and an end elevation of one of the spring rollers of the cabinet. Fig. 10 is a 55 horizontal section on line 10-10 of Fig. 11, showing the latch of the door of the cabinet. Fig. 11 is a front elevation of a portion of one corner of the cabinet. Fig. 12 is a modification, in elevation, of the controlling

levers of one side of the cabinet. And Fig. 13 is a vertical section of a portion of the block which is illustrated in Fig. 9, showing a modification of said block. Fig. 14 is a 60 section of a rotatable bearing with lever therein.

A character applied to designate a given part indicates said part throughout the several figures wherever the same appears. 65

The several corners of the cabinet are duplicates except that one thereof is provided with the slot *a* in which latch *A* enters, (see Figs. 10 and 11), and with the inclines *B*, with which disk *a* engages. 70

a' is the knob of the latch *A* and *C* is a spring under knob *a'* and on stem *a''*.

D are the strengthening plates of the end of the curtain which forms the door to the cabinet, and stem *a''* extends through an 75 aperture therefor in said plates *D*. Spring *C* tends to hold the disk *a*, (or the hub thereof) against the inner one of the plates *D*. When knob *a'* is forced in against the resilience of spring *C* the disk *a* is forced out of 80 engagement with the shoulders of inclines *B*, and the door may be opened. The door consists of the curtain *E*, and the other end of said curtain is attached to spring roller *F*, hence when the disk *a* is forced in as described, said curtain may be wound on said roller, thereby drawing stem *a''* out of slot *X*. 85

The corners of the cabinet respectively 90 comprise a metal body consisting of plates *G*, which are integrally joined. This metal body is cast or bent up, as preferred. Said corners also comprise the additional metal body *H* provided with the wings *h*, *h*, which are integral therewith and extend out from 95 the side edges thereof in planes which are parallel with the planes in which plates *G* extend. Additional body *H* is attached to body consisting of plates *G* by rivets *I*. The plates *G* are provided with any desired ornamentation. 100

J are electric lamp sockets and are secured in the body *H*.

j are the conducting wires of lamps *J*.

K are electric lamps. 105

E are the side panels of the cabinet and consist of flexible curtains which are provided with the rods *L* at one end thereof, respectively, and which are attached at the other end to the spring curtain roller *F*. 110

M (Fig. 7), are blocks which are formed of metal. Blocks *M* are provided with re-

cess m in which the end of metal body H fits; the recess m' for the end of the spring roller F , and the recess m'' for the end of the rod L . One edge of block M is provided with the groove N , and the edge adjacent to the grooved edge is provided with the tongue n . The several grooves and tongue on the edges of the blocks M are so disposed as to match or fit when the cabinet is collapsed, as is well shown in Fig. 6, to prevent end motion of the several corners to which the blocks are attached. Sides n' , n'' , of blocks M are attached to the metal bodies G , and wings h , h , of metal body H .

In the modification of block M which is illustrated in Fig. 13 said block is made in two parts, (M' and M''), and this modification is particularly adapted to be used for the top ends of the several corners.

When so used the top (O) is placed between said parts M' , M'' , (see Fig. 12.) I show said top O made of fabric in Fig. 2, and it is protected by the construction shown and described. When the cabinet is collapsed said blocks M form the ends of the package and protect the lamps from liability of breakage. Said blocks serve to close the ends of the passage ways Y , (Fig. 8), in which the conducting wires j are contained, at all times. P , Q are levers which are pivotally attached together midway of the ends thereof by pivot p , and they are pivotally attached at their lower ends to said corners by pivots q . Said levers are slidably and pivotally attached, at the upper ends thereof, to the corners by abutments R . Said abutments are pivotally attached to the corners by extending the part r of said abutments through a corresponding hole in said corners. Abutments R are provided with passage way r' therethrough, and on the back of the levers P , Q , I attach the abutment R' which extends through the aperture or passage way r' and is slidable therein. S , S' are levers, pivotally attached together at T and to the levers P , Q , at t .

U is the handle of lever S' . u is an abutment on corners adjacent to the handle U , positioned to engage with said handle U when the cabinet is collapsed. Levers S , S' maintain the levers P , Q , in an opened position, see Figs. 1 and 4. Pivot T may be on the top edge of levers S , S' , (see Fig. 4), or on the bottom edge, (Fig. 1.) When on the top edge the handle U is forced down to open the cabinet; when on the bottom edge said handle is drawn up, or raised; and to close the cabinet said handle is moved in the opposite direction.

In the modification which is illustrated in Fig. 12 a single link S'' , is pivoted at T' to lever P , and is provided with abutment T'' which engages with the slot R'' . Slot R'' is made of sufficient length to permit the required movement of abutment T'' in

the opening and closing of the cabinet. R''' are abutments on the corners, movable in slots R'' . The door of the cabinet is latched to the adjacent corner, as herein before set out, when the cabinet is collapsed, and when the cabinet is opened up by means of the levers last above described said door operates in the same manner as do the other sides or panels of the device. When the cabinet is in a usable condition the top O is opened by unbuttoning the fastenings Z, the door is opened by forcing knob a' of latch A in to release the disk a from engagement with the ends of incline B and then permitting said door to be wound on the spring roller provided therefor. The person who is to receive a bath then enters the cabinet, the door is closed and latched by latch A, and the top is buttoned after which the lamps are lighted.

In Fig. 14 the lever P is illustrated in detail with part R' turned back to form the abutment which extends through and is slidable in abutment R . The purpose of this construction is two-fold. First, to permit the placing of pivots t , t , at a farther distance from the pivot p , (that is, nearer the upper ends of levers P , Q), than said pivots t could otherwise be placed; and secondly, to strengthen the upper ends of said levers P , Q , and thereby permit the use of thin sheet metal.

In Fig. 12 the link S'' is provided with a lug or projection which moves in slot R''' in lever Q , and levers P and Q are provided with slots R'' for abutments which are positioned to engage with said levers.

I have described the corners made of bodies G and H as "metal bodies", but I do not intend thereby to confine myself to the use of metal in the construction of said corners, as fiber, or other suitable plastic and moldable material may be used, if preferred.

I claim;—

1. In a collapsible cabinet, a corner comprising a body consisting of plates which are integrally joined together at a determined angle and extending in planes which intersect on a central longitudinal line, an additional body provided with a plurality of wings extending from the edges of said body in planes which are parallel with the planes in which the first named plates extend, means to attach said wings to said plates, and blocks, with means to attach said blocks to said bodies to form ends to said corners, in combination with panels and means to attach said panels to said corners.

2. In a collapsible cabinet a corner comprising a body consisting of plates which are integrally joined together at a determined angle, an additional body provided with wings extending from the edges of

- 5 said body in planes which are parallel with said plates, means to attach said wings to said plates, and blocks, said blocks adapted to form the ends of said corners and re- 45
- 5 specifically provided with recesses, in combination with flexible panels, means to attach said panels to said blocks, with the ends of said means in said recesses, lamps and means to attach said lamps to said ad- 50
- 10 ditional body.
3. In a collapsible cabinet, a corner comprising a body consisting of plates which are integrally joined together at a determined angle, an additional, body provided 55
- 15 with wings extending in planes which are parallel with said first named plates, means to attach said wings and plates together, lamps, means to attach said lamps to said additional body, and blocks respectively at- 60
- 20 tached to and adapted to form the ends of said corner, said blocks provided with recesses, in combination with flexible panels, a spring roller, means to attach one end of one of said panels to said roller, means to 65
- 25 mount said roller in said blocks with the ends thereof in said recesses, and means to attach one end of the remaining panel to 70
- 30 said blocks.
4. In a collapsible cabinet, a plurality of corners respectively comprising a body consisting of plates which are integrally joined together at a determined angle, and an additional body provided with wings extending in planes which are parallel with said 75
- 35 plates, with means to attach said wings and plates together, electric lamps, and means to attach said lamps to said additional body, blocks respectively adapted to form the ends of said corners and means to attach said 80
- 40 blocks to said bodies, in combination with flexible panels, spring rollers, said panels attached at one end of each thereof to one of said rollers and said rollers mounted in said blocks, and said panels respectively at- 85
- tached at the other ends thereof to an adjacent corner, and grooves and ribs on engaging edges of said blocks at one of the ends of said corners.
5. In a collapsible cabinet, corners provided with faces extending in intersecting planes and panels, in combination with levers pivotally attached together between the ends thereof and to adjacent corners at one of the ends of said levers on faces of said corners which are in the same plane, 55 and means to slidably and rotatably attach the other ends of said levers to said corners on said faces.
6. In a collapsible cabinet, corners provided with faces extending in intersecting planes, and flexible panels, a spring roller in each of said corners and one end of said panels attached to said spring rollers, and means to attach the other ends of said panels in corresponding corners, in combination with levers pivotally attached together between the ends of said levers and to the corners at one of said ends of said levers, and means to slidably and rotatably attach the other ends of said levers to said 70 corners.
7. In a collapsible cabinet, corners provided with faces extending in intersecting planes, and flexible panels, a spring roller in each of said corners and one end of said 75 panels attached to said rollers, means to attach the remaining ends of said panels to said corners, in combination with levers pivotally attached together and, at one end of each thereof, to said corners, means to slidably and rotatably attach the other ends of said levers to said corners, and additional levers pivotally attached to each other and to said first named levers.

FRED F. BURDICK.
